UNITED STATES PATENT OFFICE.

SIDNEY P. JONES AND DAVID P. WALLACE, OF WACO, TEXAS.

HAIR-CLIPPER.

1,356,866.

Specification of Letters Patent. Patented Oct. 26, 1920.

Application filed January 14, 1920. Serial No. 351,369.

To all whom it may concern:

Be it known that we, SIDNEY P. JONES and DAVID P. WALLACE, citizens of the United States, residing at Waco, in the 5 county of McLennan and State of Texas, have invented certain new and useful Improvements in Hair-Clippers, of which the following is a specification.

This invention relates to new and useful 10 improvements in hair clippers.

The purpose of the invention is to provide a power driven device which will be positive in action, comprise a few number of parts, and one which will be efficient, simple 15 and easy of operation, as well as substantial and superior in arrangement and convenience.

In carrying out the invention a shoe is provided with a stationary cutter on which 20 a reciprocating cutter is mounted. A shank carries the shoe and cap which bears upon and covers the greater portion of the reciprocating cutter. By placing the cap under tension, the cutters are regulated. 25 The shank contains a novel and simple means for positively reciprocating the movable cutter. The shank is supported from a handle by a bracket, whereby the shank is off-set from the handle so that the device 30 may be conveniently held by the operator. The shoe is given a particular structure which lends to a more satisfactory manipulation of the device.

The invention will be more readily understood from a reading of the following specification and by reference to the accompanying drawings, in which an example of the invention is shown, and wherein:

Figure 1 is a plan view of a device constructed in accordance with this invention, 40

Fig. 2 is a side elevation of the same,

Fig. 3 is an underside view of the shoe and shank portions,

Fig. 4 is a longitudinal sectional view of 45 the parts shown in Fig. 3, but on an enlarged scale,

Fig. 5 is a detail of one of the cutter studs,

Fig. 6 is a side elevation of the reciprocating blade and the keeper which operates it,

Fig. 7 is a front view of said keeper,

Fig. 8 is a rear view of the keeper and the eccentric mounted therein, and

Fig. 9 is a plan view of the reciprocating cutter.

In the drawings the numeral 10 designates a shoe which has an upwardly inclined under surface 11, the latter being slid over the skin of the person. This shoe 60 has its surface 11 terminating at its lower end in a rounded heel 12 extending transversely and acting as a fulcrum on which the shoe may be rocked and obviating a sharp edge at this point. The upper surface 65 of the shoe is inclined downwardly and supports a transverse cutting blade 13. Studs 14 having beveled collars 15 are screw-threaded into the shoe so that the collars thereon are countersunk in the blade 70 13 (Fig. 5) and the latter fastened in position. The teeth of the blade project beyond the shoe and the blade has a longitudinal oil channel 16 in its upper surface.

A reciprocating blade 17 is provided with 75 slots 18 receiving the studs 14, said blade riding on the blade 13. The shoe is made integral with a tubular shank 19 and the blades have their rear edges at about the center of said shank. A cap 20 has a depending lip 21 along its front edge engaging in a groove 22 in the blade 17 just in rear of the teeth of the cutter. This lip and groove prevent the clipped hairs working back under the cap. The cap has depending 80 wings 23 overhanging the sides of the shoe and terminating flush with the bottom of said shoe. These wings have their outer surfaces rounded and conforming to the surface of the shoe. The cap has a flat upper 85 surface extending to the top of the shank. A lug 24 projecting from the rear of the cap is engaged in the top of the shank and prevents upward displacement of the cap. A spring arm 25 fastened to the cap extends 90 rearwardly and overhangs the center of the shank at which point it carries a tension screw 26 having a point engaging in the shank (Fig. 4). By adjusting the screw, the lug 24 becomes a fulcrum and the lip 21 95 100 is forced down into the groove 22 whereby the blade 17 is placed under tension. The tension may be regulated by adjusting the screw.

The blade 17 has a pair of integral fingers 105 27 projecting from its central rear portion. The blade 17 is at an incline and the fingers engage in inclined sockets 28 on each side of a keeper 29. This keeper has a vertical recess 30 (Fig. 8) in its rear side to receive 110 and confine an eccentric 31 fixed on the front end of a counter shaft 32. The keeper bears

against the rear faces of the shoe and cap and is confined between the same and a flanged bushing 33 fastened in the shank by a set screw 34. The shaft 32 is mounted in said bushing. It will be seen that the shaft revolves the eccentric 31 which displaces the keeper 29 laterally to each side of the shaft, thereby reciprocating the blade 17.

The shank is screwed into the lower front 10 side of a hollow bracket 35 in which a gear 36 is mounted on the rear end of the shaft 32. A tubular handle 37 has an annular flange 38 at its forward end internally screw-threaded to receive a collar 40 on the 15 upper rear side of the bracket. A drive shaft 39 is mounted in the handle and carries a pinion 41 on its forward end which meshes with the gear 36.

In using the device the drive shaft 39 is 20 suitably connected with a flexible shaft (not shown) in the handle and the said drive shaft thus driven by any suitable means, as an electric motor. The blade 17 is thus reciprocated very rapidly by means of the 25 shaft 33 eccentric 31 and keeper 29. The operator grasps the handle 37 and the shank 19 and shoe 10 being off-set or depending from the handle, give room for the knuckles of the operator's hand under the handle.

30 The shoe through its inclined surface 11 will ride over the skin of the person having his hair clipped in an easy and convenient manner so that the cutters perform their function very efficiently. The rounded heel 12 35 permits the shoe to be easily rocked, whereby the cutters may be swung outward in finishing the upward stroke. The arm 25 is pivoted on the cap and may be swung to one side so that the cap may be swung upward 40 and pulled outward to withdraw the lug 24 and remove the cap. The blade 17 may be lifted from the studs, whereby the keeper will be lifted, after which said blade may be pulled outward and removed. By unscrewing 45 the studs 14 the blade 13 may be removed.

What we claim, is:

1. In a hair clipping device, a support, a pair of cutters mounted on the support, a 50 pair of fingers carried by one cutter and projecting rearwardly, a shank carrying the support, a reciprocating keeper mounted in the support and having a pair of grooves to receive said fingers, a counter shaft mounted in the shank, and an eccentric mounted on the counter shaft and engaging in the keeper.

2. In a hair clipping device, a tubular shank, a shoe carried by the forward end 60 of the tubular shank, a pair of co-acting blades having teeth and arranged in superposed relation upon the shoe, the upper blade having a groove upon its upper surface extending transversely of the tubular shank, 65 a removable cap adapted to cover the rear

portions of the blades and provided near its forward end with a depending lip extending into the groove for forming a joint to prevent the passage of cut hair beneath the cap, means for retaining the cap in place, and 70 means arranged within the tubular shank for moving one blade.

3. In a hair clipping device, a shoe, a blade removably fastened on the shoe, a reciprocating blade mounted on the stationary 75 blade and having a groove, a readily removable cap having a lip engaging in the groove, a shank supporting the shoe, a spring arm mounted on the cap and overhanging the shank, a tension screw mounted in the arm 80 and engaging the shank, a keeper mounted in the shank and engaging the reciprocating blade, a counter shaft in the shank, an eccentric on the counter shaft engaging in the keeper, a bushing in the shank and receiving 85 the countershaft and slidably engaging the keeper, a hollow bracket supporting the shank, gears in the bracket connected with the counter shaft, a handle engaging the bracket, and a drive shaft mounted in the 90 handle and connected with the gears.

4. In a hair clipping device, a tubular shank, a shoe carried by the forward end of the tubular shaft, a pair of co-acting blades having teeth and arranged in superposed relation upon the shoe, the upper blade having a groove upon its upper surface extending transversely of the tubular shank, a removable cap adapted to cover the rear portions 95 of the blades and provided at its forward end with a depending lip extending into the groove for forming a close joint to prevent the passage of cut hair beneath the cap, a lug carried by the rear end of the cap and extending into the tubular shank and serving as a pivot for the cap, and a leaf spring connected with the cap forwardly of the lug and engaging the tubular shank to force the cap downwardly, and means arranged within the tubular shank to move one of the 100 blades.

5. In a hair clipping device, a tubular shank, a shoe carried by the forward end of the tubular shank, a pair of co-acting blades having teeth and arranged in superposed 115 relation upon the shoe, the upper blade having a groove upon its upper surface extending transversely of the tubular shank, a removable cap to cover the rear portions of the blades, and provided at its forward 120 end with a depending rib extending into the groove, a lug carried by the rear end of the cap and extending into the tubular shank, a leaf spring secured to the cap forwardly of the lug and extending rearwardly 125 over the tubular shank, a tension screw carried by the spring and engaging the shank, and means arranged within the tubular shank to move one blade.

6. In a hair clipping device, a tubular 130

shank, a shoe carried by the forward end of the tubular shank, a pair of co-acting blades having teeth and arranged in superposed relation upon the shoe, a removable cap to cover the rear portions of the blades and having its forward end slidably engaging the upper blade for forming a close fit therewith, a lug carried by the rear end of the cap and entering the shank, means

10 to force the forward end of the cap downwardly, and means arranged within the tubular shank to move one blade.

7. In a hair clipping device, a tubular shank, a shoe carried by the forward end of the tubular shank and provided with a sharply inclined lower surface and a rounded heel at the lower end of such surface, said

heel extending downwardly below the tubular shank, a pair of blades arranged upon the upper side of the shoe, a gear casing connected with the rear end of the tubular shank and extending upwardly beyond the same, a handle connected with the upper end of the gear casing whereby the handle is offset upwardly with relation to said shoe, a driving shaft carried by the handle, the gears arranged within the gear case and driven by the driving shaft, and operating means within the tubular shank to move one blade and driven by said gears.

15 In testimony whereof we affix our signatures.

SIDNEY P. JONES.
DAVID P. WALLACE.
